CLAIM

The ornamental design for a luminaire joint as shown and described.

DESCRIPTION

FIG. 1 is a bottom perspective view of a luminaire joint in a first position;

FIG. 2 is a top perspective view thereof;

FIG. 3 is a left elevation view thereof;

FIG. 4 is a right elevation view thereof;

FIG. 5 is a top view thereof;

FIG. 6 is a bottom view thereof;

FIG. 7 is a front elevation view thereof;

FIG. 8 is a rear elevation view thereof;

FIG. 9 is a bottom perspective view of the luminaire joint in a second position;

FIG. 10 is a top perspective view thereof;

FIG. 11 is a left elevation view thereof;

FIG. 12 is a right elevation view thereof;

FIG. 13 is a top view thereof;

FIG. 14 is a bottom view thereof;

FIG. 15 is a rear elevation view thereof; and,

FIG. 16 is a front elevation view thereof.

The broken lines in FIGS. 1-16 represent portions of the luminaire joint and environment that form no part of the claimed design.

1 Claim, 16 Drawing Sheets
